(57) **CLAIM**

The ornamental design for a valve, as shown.

DESCRIPTION

FIG. 1 is a perspective view of a valve according to our new ornamental design;

FIG. 2 is a right side view thereof;

FIG. 3 is a left side view thereof;

FIG. 4 is a front view thereof;

FIG. 5 is a rear view thereof;

FIG. 6 is a bottom view thereof; and,

FIG. 7 is a top view thereof.

The broken lines shown in the figures are included for the purpose of illustrating portions of the valve and form no part of the claimed design.
